Filed Apr. 3, 1967, Ser. No. 6,503

Term of patent 14 years

(Cl. D86—8)

FIG. 1

FIG. 2

FIG. 3

FIG. 4

FIGURE 1 is a front perspective view of a hair comb showing my new design;

The characteristic feature of my design resides in the combination on the hair comb disclosed of the relatively short teeth on each side, one set of teeth having their attached ends and their free ends disposed along parallel lines and the other set of teeth having their attached ends and their free ends disposed along markedly curved lines, and the central rib or backbone portion having a first straight ridge on each opposite face inset from the attached ends of said one set of teeth and having a second curved ridge on each opposite face inset from the attached ends of said other set of teeth corresponding to the curvature of the attached ends and the free ends of said other set of teeth, all as shown.

I claim:

The ornamental design for a hair comb, as shown and described.
